HINGED LAST

Eugene J. Dumas, Salem, Mass., assignor, by
mesne assignments, of one-half to Daniel W.
Benham, Middleton, Mass., and one-half to
Lewis Siegel, Lynn, Mass., doing business as
North Shore Last Co.

Application October 1, 1934, Serial No. 746,307

18 Claims. (Cl. 12—136)

This invention relates to hinged lasts and has for its object the production of a novel connector between the two parts of the last which will hold said parts rigidly together when either in extended or shortened position while permitting slight relative movement of said parts toward and from each other at intermediate points. 5
This object is attained by the mechanism illustrated in the accompanying drawing.
10 For the purpose of illustrating the invention, one preferred form thereof is illustrated in the drawing, this form having been found to give satisfactory and reliable results, although it is to be understood that the various instrumentalities 15 of which the invention consists can be variously arranged and organized, and the invention is not limited to the precise arrangement and organization of these instrumentalities as herein shown and described except as required by the scope of 20 the appended claims.

Of the drawing

Figure 1 represents a longitudinal vertical section of a two-part last, the two parts of which are 25 hinged together by a connector embodying the principles of the present invention, the last being shown extended.

Figure 2 represents a similar section showing the last shortened.

Figure 3 represents a horizontal section of a 30 portion of the last, on line 3, 3 of Fig. 1.

Figure 4 represents an elevation of an outer plate forming a part of the hinge connection.

Figure 5 represents an elevation of the inner 35 plate of said hinge connection.

Figure 6 represents an elevation of a modified form of hinge connection with an actuating spring therein.

Figure 7 represents an elevation of the inner 40 plate of the modified form of hinge connection, and

Figure 8 represents a plan of the spring of said hinged connections.

Similar characters indicate like parts throughout the several figures of the drawing.

In the drawing, 10 is the fore part of a divided last having formed in its rear face a curved depression 11 extending transversely thereof.

The heel part 12 has formed on its front face a semi-cylindrical projection 13 adapted to be positioned in the depression 11 and contact with the wall thereof.

The depression 11 is semi-cylindrical and has a radius slightly exceeding that of the semi-cylindrical projection 13.

Owing to the differences in the radii of the

projection 13 and depression 11, the outer surface of the projection 13 will not contact with the surface of the depression 11 at the top and bottom thereof.

The fore part 10 is provided with a vertical slot 14 in its rear end which is aligned with a similar slot 15 formed in the front end of the heel part 12.

In the slots 14, 15 are disposed a plurality of hinged elements or links 16, 17 and 18, these links 10 being of hardened steel and provided with holes 19, 19x in the opposite ends thereof, the hole 19x being elongated as shown in the drawing while the holes 19 are cylindrical.

Through these holes 19, 19x extend hardened 15 steel pins 20 positioned in the fore part 10 and heel part 12 and extending transversely of the links 16, 17 and 18 and midway of the length thereof are openings 21.

When the links 16, 17 and 18 are disposed in the 20 slots 14 and 15, the central links 17 will be oppositely disposed to the outer links 16 and 18, or in other words the holes 19 in the outer links 16 and 18 will be at the left as in the drawing while the hole 19 of the middle link 17 will be at the right. 25

By providing in each link 16, 17 and 18 cylindrical pin holes 19 and elongated pin holes 19x and placing these links on the pins 20 with the inner link 17 reversed from the portion of the outer links 16, 18, said links may be moved relatively to each other when the last is being lengthened or shortened.

In the openings 21 of said links are disposed two curved springs 22, the ends of which are anchored to the links in the recesses 23 so that 35 said springs 22 cannot be displaced during the operation of the last in shortening or lengthening.

In some cases it may be desirable to use a single curved spring 24 as shown in Fig. 6, the ends of 40 which are anchored in the notches 25.

In either case the springs 22 and 24 have a width equal to the combined thickness of the three links 16, 17 and 18 and when positioned in the openings 21 the material of the outer links 16, 18 is slightly upset so as to impinge upon the 45 ends of the springs 22 or 24, thus preventing the separation of the links while permitting the inner link 17 to move endwise relatively to the outer links 16, 18, thus increasing the length of the hinge connection.

Built up in this manner the hinge connection is complete in itself and may be sold by itself to manufacturers who prefer to turn their own lasts and then apply the hinge connection thereto. 50 When the last is straightened as shown in Fig. 55

1 of the drawing, a portion of the periphery of the semi-cylindrical projection 13 will be held in rigid contact with the central portion of the depressions 11 and the center line *a*, *a*, of the links 16, 17 and 18 will be considerably below the axis 26 of the projection 13.

5. When shortening the last by moving the fore part 10 about the axis 26 and relatively to the heel part 12, said axis 26 must move toward the bottom of the last and pass across the line *a*, *a*, (indicated in Fig. 2) drawn between the centers of the pins 20.

10 Owing to this center line *a*, *a* being well below the axis 26 of the projection 13, the fore part can be moved about said axis in order to shorten the last only by applying great pressure thereto.

15 As this pressure is applied to the fore part to move it about said axis 26, the links 16, 17 and 18 will move sufficiently relatively to each other to permit this movement and then return to their normal position.

20 Even when the last is shortened and in the position indicated in Fig. 2 of the drawing, it is only by applying considerable pressure to the fore part that it may be moved about the axis 26 to extend the last into the position indicated in Fig. 1.

25 As a consequence, the two parts 10, 12 of the last are connected in such a manner that the last is very rigid when in either shortened or extended position.

30 It will be noted that upon breaking the last when in its extended position, the last will immediately commence to shorten.

35 In the preferred form of hinge connection shown in Figs. 1 to 5 inclusive, the centers of the curved springs 22, contact with each other and when the central link 17 is moved relatively to links 16, 18 from its normal position to lengthen 40 the hinge connection, the springs will be slightly buckled but as soon as the lengthening of the hinge connection is no longer required the springs 22 will return the links 16, 17 and 18 to their normal positions.

45 The same action occurs when the single spring 24 is used.

50 The links 16, 17 and 18 forming the hinged connection between the pivot pins 20 of the fore part 10 and heel part 12 may be quickly and cheaply constructed thereby reducing the expense of manufacture.

55 Obviously when a shoe is on a last and being operated upon in the manufacture thereof, it is quite essential that the last should have a great degree of rigidity and this result is produced very effectually by the construction herein shown and described.

60 It is believed that the operation and many advantages of the invention will be understood without further description.

Having thus described my invention, I claim:

1. A two-part last, the parts of which are movable about a predetermined axis and provided with aligned vertical slots; transverse pins in said parts extending across said slots; a connector in said slots through the opposite ends of which said pins extend, said connector consisting of a plurality of plates having elongated openings therein, one of said plates having an elongated hole in one end and another having an elongated pin hole in the opposite end; and a curved spring plate within said openings and engaging both plates between said pins.

70 2. A two-part last, the parts of which are movable about a predetermined axis and provided

75 with aligned vertical slots; a hinge connection between said parts disposed in said slots consisting of three contacting plates, the center plate being movable endwise relatively to the outer plates; and means coacting with all of said plates for retaining said last parts normally in shortened position.

3. A two-part last, the parts of which are movable about a predetermined axis and provided with aligned vertical slots; a hinge connection between said parts disposed in said slots consisting of three contacting plates, the center plate being movable endwise relatively to the outer plates; and a spring confined within and engaging all of said plates for retaining said last parts normally in shortened position.

4. A two-part last, the parts of which are movable about a predetermined axis and provided with aligned vertical slots; a hinge connection between said parts disposed in said slots consisting of three contacting plates, the center plate being movable endwise relatively to the outer plates; and two curved flat spring plates with their centers in contact and their ends coacting with all of said plates for retaining said last parts normally in shortened position.

5. A two-part last, the parts of which are movable about a predetermined axis and provided with aligned vertical slots; a hinge connection between said parts disposed in said slots consisting of three contacting plates, the center plate being movable endwise relatively to the outer plates; and an arcuate flat spring positioned in an elongated opening in and with its ends engaging all of said plates for retaining said last parts normally in shortened position.

6. A two-part last, the parts of which are movable about a predetermined axis and provided with aligned vertical slots; a hinge connection between said parts comprising a plurality of contiguous plates movable endwise relatively to each other, said connection axis being below the axis of the last when it is extended; pins in said last parts extending through the opposite ends of all of said plates; and means confined within said plates whereby the hinge connection may be lengthened during the movement of said parts relatively to each other and then be shortened at the end of said movement.

7. A two-part last, the parts of which have abutting curved surfaces movable about a predetermined axis and provided with aligned vertical slots; transverse pins in said parts extending across said slots; a connector in said slots for retaining said surfaces in contact and through the opposite ends of which said pins extend, said connector consisting of a plurality of plates having elongated openings therein, one of said plates having an elongated pin hole in one end and another having an elongated pin hole in the opposite end; and a curved spring plate engaging both plates between said pins.

8. A two-part last, the parts of which have abutting curved surfaces movable about a predetermined axis and provided with aligned vertical slots; a connector in said slot with its ends pivotally connected to said parts adapted to retain said surfaces in contact and consisting of a plurality of plates having movement endwise relatively to each other; pins in said last parts extending through the opposite ends of all of said plates; and means confined within and coacting with said plates for retaining the last parts normally in shortened position.

75 9. A two-part last, the parts of which have

- abutting curved surfaces movable about a predetermined axis and provided with aligned vertical slots; a hinge connection between said parts disposed in said slots adapted to retain said surfaces in contact and consisting of a plurality of flat sided contacting plates movable endwise relatively to each other; pins in said last parts extending through the opposite ends of all of said plates; and means confined within said plates for retaining said last parts normally in shortened position.
10. A two-part last, the parts of which have abutting curved surfaces movable about a predetermined axis and provided with aligned vertical slots; a hinge connection between said parts disposed in said slots adapted to retain said surfaces in contact and consisting of three contacting plates, the center plate being movable endwise relatively to the outer plates; and means confined within said plates for retaining said parts normally in shortened position.
11. A two-part last, the parts of which have abutting curved surfaces movable about a predetermined axis and provided with aligned vertical slots; a hinge connection between said parts disposed in said slots adapted to retain said surfaces in contact and consisting of three contacting plates, the center plate being movable endwise relatively to the outer plates; and a flat spring confined within and engaging all of said plates for retaining said last parts normally in shortened position.
12. A two-part last, the parts of which have abutting curved surfaces movable about a predetermined axis and provided with aligned vertical slots; a hinge connection between said parts disposed in said slots adapted to retain said surfaces in contact and consisting of three contacting plates, the center plate being movable endwise relatively to the outer plates; and confined within said plates two curved flat spring plates with their centers in contact and their ends coacting with all of said plates for retaining said last parts normally in shortened position.
13. A two-part last, the parts of which have abutting curved surfaces movable about a predetermined axis and provided with aligned vertical slots; a hinge connection between said parts disposed in said slots adapted to retain said surfaces in contact and consisting of three contacting plates, the center plate being movable endwise relatively to the outer plates; and an arcuate flat spring positioned in an elongated opening in and engaging all of said plates for retaining said last parts normally in shortened position.
14. A two-part last, the parts of which have abutting curved surfaces movable about a predetermined axis and provided with aligned vertical slots, the curved surface in the fore part forming a socket having a radius slightly exceeding that of the curved projection on the heel part disposed in said socket; a hinge connection between said parts adapted to retain said surfaces in contact and comprising a plurality of contiguous plates movable endwise relatively to each other, said connection axis being below the axis of the last when it is extended; pins in said last parts extending through the opposite ends of all of said plates; and means confined within and coacting with all of said plates whereby the hinge connection may be lengthened during the movement of said parts relatively to each other and then shortened at the end of said movement.
15. A hinge connection for a two-part last consisting of a plurality of plates having elongated central openings therein and pin holes at opposite ends, one of which is cylindrical and the other elongated, the cylindrical hole of one plate being opposite the elongated hole of an adjacent plate; and a spring member disposed in said openings with its ends engaging all of said plates.
16. A hinge connection for a two-part last consisting of a plurality of plates having elongated central openings therein and pin holes at opposite ends, one of which is cylindrical and the other elongated, the cylindrical hole of one plate being opposite the elongated hole of an adjacent plate; and two curved spring plates disposed in said openings with their ends in recesses in all of said plates.
17. A hinge connection for a two-part last consisting of a plurality of plates having elongated central openings therein and pin holes at opposite ends, one of which is cylindrical and the other elongated, the cylindrical hole of one plate being opposite the elongated hole of an adjacent plate, a spring member disposed in said openings with its ends engaging all of said plates; and means preventing lateral separation of said plates.
18. A hinge connection for a two-part last consisting of a plurality of plates having elongated central openings therein and pin holes at opposite ends, one of which is cylindrical and the other elongated, the cylindrical hole of one plate being opposite the elongated hole of an adjacent plate, and a curved spring plate disposed in said openings with its ends engaging all of said plates.

EUGENE J. DUMAS. 55
